ABSTRACT OF THE DISCLOSURE

A movable, weighted, elongated member presenting an upwardly and rearwardly extending wall to provide a movable back for an ink fountain reservoir. A longitudinally extending flange on the lowermost edge of the front wall bears against the bottom of the fountain reservoir to confine the ink between the member and the fountain roller. An elongated rod carried by the flange holds the member in place on the inclined bottom of the fountain reservoir. In one form of the invention, the rod is segmented for selectively varying the weight of the structure.

This invention relates to printing presses and, more particularly, to a movable wall structure for the ink reservoir of such presses. In the printing of certain items such as those utilizing magnetic ink for automatic machine recording, classifying or sorting, it is especially important that the ink which is in the fountain reservoir be kept concentrated in a position so that it is readily available to the fountain roller.

It is also important that magnetic inks be available for uniform distribution by the components of a printing press so that each of the items printed will be provided with a sufficient quantity of ink having magnetic properties for proper detection by automatic sorting machines and the like. It is, however, particularly difficult to maintain inks which contain relatively heavy magnetic constituents concentrated in a proper mass for uniform distribution by the fountain roller because such inks tend to be relatively heavy and settle back away from the fountain roller under the influence of gravity and operation of the fountain roller. When the ink in the reservoir is permitted to spread substantially over the bottom surface thereof under the influence of gravity and movement of the roller, such settling tends to locate the ink where it is not readily picked up by the fountain roller which transfers the ink to the using components of the printing press. If a thinner is added to the ink, a condition may result where the thinning liquid and only a small amount of magnetic particles are in contact with the fountain roller.

Various attempts have been made at providing means for concentrating the ink in the reservoir. Devices have heretofore been suggested for holding the ink in proper location with respect to the fountain roller and to achieve automatic agitation of the ink by the fountain roller. However, these devices have been relatively expensive, time consuming to assemble, and usually require modification of the printing press.

It is, therefore, the most important object of this invention to provide a simple, inexpensive, yet highly reliable, movable back wall structure for a fountain reservoir to hold the ink in proper position for supplying an adhering film of ink to the fountain roller for subsequent distribution to the printing components of a printing press.

In the achievement of the foregoing object, it is also an important object of the present invention to present structure which is readily portable but which will maintain a given location when positioned on the bottom wall of an ink fountain.

It is another important object of this invention to pro-

2

vide such back wall structure which is simple and easy to operate and which may be installed or removed from the ink fountain without the necessity of modification thereto.

These and other important objects of this invention will be further explained or will become apparent from the following description, claims and drawing, wherein:

FIGURE 1 is a vertical, cross-sectional view through a typical ink fountain and fountain roller illustrating the structure of this invention in place on the bottom wall of the ink reservoir;

FIG. 2 is a bottom perspective view on a reduced scale of the structure of this invention, illustrating the form thereof having no end caps;

FIG. 3 is an end elevational view of the structure of this invention illustrating the form provided with end caps;

FIG. 4 is a fragmentary, front elevational view of the structure of FIG. 3; and

FIG. 5 is a view similar to FIG. 4, parts being broken away to reveal details of construction.

The structure embodying the principles of this invention is designated by the numeral 10 and is illustrated in FIG. 1 in position on the bottom wall 12 of an ink fountain 14. The latter includes a fountain bed knife 16 provided with a fountain blade 18 disposed at an angle with respect to the horizontal by virtue of thumbscrews 20 and 22 received within frame 24. A fountain bed roller 26 is positioned immediately adjacent the forwardmost longitudinal edge of blade 18 to form one side of the fountain reservoir defined by roller 26, blade 18 and endwalls 28.

The quantity of ink in the fountain reservoir is designated schematically in FIG. 1 as 30. It is apparent that the ink 30 would cover a relatively large portion of wall 12 by virtue of the action of gravity upon the ink mass were it not for the interposition of structure 10 as illustrated.

Structure 10 comprises an elongated, relatively rigid member 32 of sheet material bent into generally triangular cross-sectional configuration to present an upwardly and rearwardly inclined front wall 34 which merges along a rounded edge 36 into an integral, downwardly and rearwardly extending rear wall 38 which serves as a support for structure 10. Rear wall 38 is provided along its lowermost edge with an integral, rearwardly extending flange 40, the lowermost portion of which provides a surface which engages the upper surface of the bottom wall 12 of the reservoir.

The lowermost longitudinal edge of front wall 34 is integral with and merges into a rearwardly and generally upwardly extending flange 42 which engages the bottom wall 12 of the reservoir to provide a second support for structure 10. An elongated, relatively thin strip of gasket material 44 or the like is secured to the lowermost surface of flange 42 for effecting an ink-tight seal along the entire length of flange 42. The latter is bent to extend at an acute angle from wall 34 and an elongated weight rod 46 (which may be of transversely circular configuration as illustrated) is carried on flange 42 and against the rear surface of front wall 34.

Referring now to FIG. 2, it will be seen that rod 46 may be divided into segments 46a, 46b and 46c, whereupon the weight of the composite unit may be selectively varied if desired. Handle means 48 is mounted on the rear surface of rear wall 38 of structure 10 to facilitate manual manipulation of the latter.

As illustrated in FIGS. 3, 4 and 5, structure 10 may be provided with end plugs 50 to prevent the admission of any ink into structure 10 at the ends of member 32. Plugs 50 include a peripheral rim 52 and an integral extension 54 recessed from the outer periphery of rim 52 to receive the member 32 on the outer surface of exten-

sion 54. Plugs 50 are thus frictionally retained in place at the respective ends of structure 10 but do not prevent the sealing of material 44 against the upper surface of bottom 18 of the reservoir. Manifestly, structure 10 could be used without end plugs 50 if care is taken in the use of the structure inasmuch as the latter normally extends substantially the entire width of the ink reservoir and the possibility of ink flowing into the open ends of structure 10 is thereby minimized.

Although the angles of bends of member 32 to provide the flanges 40 and 42 and the front and rear walls 34 and 38 respectively are not critical, it is intended that structure 10 will be configured so that front wall 34 extends upwardly at an angle which is approximately 80° from horizontal when structure 10 is in position in the fountain 15 reservoir. This angle will permit confining of the ink as is desirable for achieving proper ink distribution by the fountain roller.

As is clearly illustrated in FIG. 1, the operator of the printing press may grasp structure 10 by means of handle 48 and install the structure in the ink reservoir at any desired spacing from the fountain roller 26. The upwardly and rearwardly inclined wall 34 thereby serves to confine the ink mass within limits which will permit pickup by the fountain roller of a desirable film of ink as the fountain roller 26 rotates in the direction of the arrow in FIG. 1. The general path of agitation of the ink mass 30 is illustrated schematically by a series of arrows and shows how the ink is conducted by the front wall 34 of structure 10 in an upwardly and rearwardly direction 30 to the upper surface of the mass 30. The ink is thereupon pulled forwardly and downwardly by the rotation of fountain roller 26 for distribution by a saddle roller 56 to other components of the press.

Weight 46 insures that structure 10 will seat securely 35 when positioned on the inclined bottom wall 12 of the fountain reservoir to preclude inadvertent movement of structure 10 and also, to prevent the flowing of ink between the seal effected by material 44 against the upper surface of the bottom wall. Manifestly, the amount of 40 weight necessary for accomplishing this purpose may vary. Accordingly, it is desirable that the weight of the entire assembly be variable. This variation can, of course, be quickly and easily carried out by virtue of the segmented weight rod 46 illustrated in FIG. 2. One or more 45 of the segments may be removed to effect such weight change as may be desired.

Having thus described the invention, what is claimed as new and desired to be secured by Letters Patent is:

1. For use with an ink fountain for a printing press 50

or the like, including an ink reservoir having an inclined bottom and an ink dispensing roller forming one side of the reservoir, movable back wall structure for said reservoir comprising:

5 an elongated, rigid member of sheet material bent in substantially triangular cross-sectional configuration to present an upwardly and rearwardly extending front wall and a downwardly and rearwardly extending gear wall;

a rearwardly extending flange integral with the lowermost edge of said front wall and adapted to rest on said fountain bottom to confine the ink in said reservoir between the front wall and said roller; and

weight means carried by said member between said flange and the rear surface of said front wall to hold said structure in firm engagement against said bottom.

2. The invention of claim 1, said weight means including an elongated bar of relatively heavy material.

3. The invention of claim 2, said bar being divided into a plurality of segments whereby the weight of said structure may be altered by removal of any of said segments.

25 4. The invention of claim 2, wherein is included gasket means carried by said flange on the lowermost surface thereof and adapted to engage the bottom of said reservoir to enhance the ink seal between said structure and said bottom.

5. The invention of claim 4, wherein is included a plug for each end of said member respectively, said plugs extending in covering relationship across said ends between said front and rear walls and said flange to preclude the flowing of ink into said member through said ends.

6. The invention of claim 5, wherein is included handle means mounted on said rear member in disposition to facilitate manual manipulation of said member along said bottom.
